UNITED STATES PATENT OFFICE

GRACE G. DRAYTON, OF NEW YORK, N. Y.

DESIGN FOR A DOLL TOY

Application filed February 7, 1931. Serial No. 38,582. Term of patent 7 years.

To all whom it may concern:

Be it known that I, GRACE G. DRAYTON, a citizen of the United States, residing at No. 145 East 52nd Street, in the borough of Manhattan, city, county and State of New York, have invented a new, original and ornamental Design for a Doll Toy of which the following is a specification, reference being had to the accompanying drawing forming a part thereof, and showing in Fig. 1 a front view and in Fig. 2 a side view of the doll toy embodying my design.

I claim:

The ornamental design for a doll toy substantially as shown.

GRACE G. DRAYTON.
